UNITED STATES PATENT OFFICE.

WILLIAM L. RATHJEN AND LILLIAN K. RATHJEN, OF OAKLAND, CALIFORNIA.

HOT-AIR DEVICE.

Application filed August 14, 1924, Serial No. 731,994. Renewed January 15, 1927.

Our invention relates to hot-air devices, and more particularly to hot-air hair dryers of a portable nature and for home use primarily.

5 The present dryers for washed and wet hair that we are familiar with, are motor-driven electric ones and consequently expensive and in fact too costly for the average home, so our chief object is the production of 10 a simple, durable and efficient hair dryer of a mechanical nature and one that can be sold at a comparatively low price.

Another object is to make it of sheet metal and as a portable unit and without any moving parts.

15 Another object is to make the dryer serviceable for use on a gas plate, coal stove, electric stove, or other heat-emitting apparatus.

20 A further object is to affix a hair guard to the device for marcelling the hair and also to prevent long hair from coming into too close proximity to the heating element.

We attain the above objects by the novel 25 construction of our device, and other objects and advantages of the invention will appear in the subjoined description of the accompanying sheet of drawings, in which:

Figure 1 is a plan of the invention, and 30 Fig. 2 a vertical longitudinal section through the same; and Fig. 3 is a front elevation of it with the hair guard removed and showing to advantage the hot-air outlet of the device.

35 Adverting to the drawings we will now describe the same in detail: The numeral 4 indicates the shell of the invention and it is preferably formed of sheet-metal material. The shell has a full open bottom 5 which is the inlet for the air, and has an 40 opening 6 at its top which is the outlet for the heated air, and the said outlet is of small area compared to that of the inlet. By preference, the outlet 6 is of slot-like formation and is exposed transversely.

45 The shell is constructed so that the outlet overhangs the inlet as shown at 7, the overhang serving as an intermediate guard to prevent one getting too close to the burner element.

50 The dot-and-dash line 8 represents the surface of a gas plate, coal stove, electric stove, or other heat-radiating surface, and upon which the hot-air device is placed; in the case of a gas plate, the device is set directly over the gas burner.

55 Within the shell are walls 9, 10 and 11,

spaced transversely and apart, forming chambers A, B and C. These chambers, as shown, are open top and bottom. At the bottom they open into the common inlet 5, 60 and at the top open into the common outlet 6. The said transverse walls increase the heating surface and add to the efficiency of the device, and there may be as many walls and chambers as desired. The intermediate 65 walls 9 and 10 may terminate above the base of the opening 5 as shown at 12, so that when the device is placed over a flat heating surface, such as a coal stove for example, the inlet opening 5 will still be common to 70 the said chambers A, B, and C. In the last-named application, additional air inlets must be provided, and we choose to have the inlets in both sides of the shell and at or near the base, such as shown at 13, Fig. 2, 75 and we may have any number of them.

Above the said chambers, we employ an additional chamber D, having a separate and distinct opening 14 for the inlet of cold air taken above the heating surface 8. The outlet 15 of this chamber joins the common outlet 6.

80 All the transverse walls converge toward the common outlet 6, and the uppermost wall 16 of the shell terminates substantially 85 in a horizontal plane and lies over the mouth of the outlet as at 17 and for a purpose to be presently given.

85 Surmounted on the top of the lip is a handle 18 for portable purposes, and a guard 90 19 for spacing the long hair 20 a safe distance from the source of heat. The guard is preferably formed of spring wire, and its terminals are bent to form pivot points 21 and shoulders 22 near thereto. The points 95 enter perforations 23 in each side of the shell, and the shoulders 22 rest on the top of the lip 17. The spacing end of the guard may be comparatively wide and have prong-like points or limits 24, and intermediate 100 said points the wire may be formed wave-like as shown at 25, the reason being presently set forth.

When it is desired to remove or swing back the hair guard from service, simply 105 spring out the points 21 from the shell, or swing the guard back on the said pivot points to the limiting rest position shown in portion at 26, Fig. 2.

In operation, the device is set over the 110 heating element. Immediately the big volume of heated air, represented by the wavy

arrows, rises and is deflected by the transverse walls to the narrow and restricted outlet 6. Here the said volume of heated air, together with the layer of comparatively cold air, represented by the unwaved arrows, sucked through chamber D, pass through the common outlet rapidly and under a very perceptible pressure by reason of the restricted outlet, and is deflected horizontally by the lip 17. The issuing hot air then spreads fan-like and is held from rising too abruptly by the blanket, so to speak, of the said top layer of cooler and heavier air passing through the chamber D.

15 Wet hair is dried by the hot-air blast in a very few minutes, and when the wet hair is in the guard and contacting the wave-like front, the resultant dried hair has the appearance of being marcelled at such contacted areas, the user of the device contacting the various portions of her hair on the wave-like front 25 during the drying period.

From the foregoing description taken in connection with the accompanying drawings, the advantages of the construction and method of operation will be readily understood by those skilled in the art to which the invention appertains, and while we have described the principle of operation, together with the device which we now consider to be the best embodiment thereof, we desire to have it understood that the device shown is merely illustrative and that such changes may be made, when desired, as fall within the scope of the appended claims.

Having thus described our invention, what we claim as new and desire to secure by Letters Patent of the United States, is the following:

- 40 1. A hot-air device of the class described, comprising a shell having two openings, one being the inlet and of large area and the other the outlet and of small area compared to that of the inlet, and said outlet adapted for the issuance of the hot air at a pressure and velocity greater than that of the inlet air, and the said shell having a wall therein for additional heating surface and for directing the heat waves to the said outlet.
- 45 2. A hot-air device of the class described, comprising a shell having two openings, one being the inlet and of large area and the other the outlet and of small area compared

to that of the inlet, and said outlet adapted for the issuance of the hot air at a pressure 55 and velocity greater than that of the inlet air, and the said shell having a wall therein for additional heating surface and for directing the heat waves to the said outlet, and the sides of said shell provided with openings at its base for the inlet of air when the device is used on a flat and continuous heat-radiating surface.

3. A hot-air device of the class described, comprising a shell having two openings, one 65 being the inlet and of large area and the other the outlet and of small area compared to that of the inlet, and said outlet adapted for the issuance of the hot air at a pressure 70 and velocity greater than that of the inlet air, and the said shell converging from the inlet opening to the outlet opening, the latter opening overhanging the inlet opening to prevent too close proximity to the heating element.

4. A hot-air device, comprising a shell having a plurality of spaced walls therein forming a plurality of heating chambers having a common inlet opening and converging toward a common outlet opening, 80 and said chambers having thereabove an additional chamber with a separate inlet opening for cold air and terminating in the said common outlet opening.

5. A hot-air device, comprising a shell 85 having a plurality of spaced walls therein forming a plurality of heating chambers having a common inlet opening and converging toward a common outlet opening, 90 and said chambers having thereabove an additional chamber with a separate inlet opening for cold air and terminating in the said common outlet opening, and a hair guard mounted above said outlet opening and extending outwardly therefrom.

95 6. In a hair-drying device of the class described, a hair guard adapted to extend therefrom and having its outermost edge formed prong-like and between said prongs having the edge formed wave-like to marcel the wet hair in contact therewith in the drying of the hair.

In testimony whereof we affix our signatures.

WILLIAM L. RATHJEN.
